ABSTRACT: An air-conditioning system including first and second central station apparatus for supplying conditioned primary and secondary air, respectively, to a plurality of enclosed areas in a building. A constant volume of secondary air is supplied to a preselected area. The temperature of the area is sensed and the first central station apparatus is operated to provide a constant volume of primary air to each of the enclosed areas at a temperature related to the temperature sensed in the preselected enclosed area. Secondary air is supplied to each of the other areas simultaneously with the supply of secondary air to the preselected area, the volume thereof being regulated to provide a desired temperature condition in each of the areas.

DUAL CONDUIT AIR-CONDITIONING SYSTEM

BACKGROUND OF THE INVENTION

This invention relates to air conditioning apparatus or systems and more particularly to a method and system of the so-called dual conduit type for conditioning a building structure containing a plurality of enclosed areas.

A dual conduit system is designed to supply two airstreams to enclosed areas that have a reversing transmission load; that is, during summer, heat flows from the ambient air into the building, whereas during winter, heat flows from the building to the ambient air. One airstream, called the secondary air, is cooled the year round and is constant in temperature and variable in volume.

The other airstream, called the primary air, is constant in volume and the air temperature is varied; it is warm in winter and cool in summer. The primary air is, therefore, a constant volume-variable temperature airstream. To obtain the two airstreams, central station apparatus is employed to provide the air temperatures and volumes required.

The primary air apparatus varies the psychometric properties of the air supplied thereto, which may consist of a mixture of outdoor and return air. The apparatus contains filters to remove dirt or foreign matter entrained in the air, preheat coils as required to temper coil winter air, a humidifier to add winter humidification and a dehumidifier to remove excess moisture and to cool the supply air furnished at a constant volume to the enclosed areas contained in the building equipped with a system constructed in accordance with this invention.

The secondary air apparatus also varies the psychometric properties of the air supplied thereto and supplies either all return air, a mixture of outdoor and return air or all outdoor air, depending upon the season. The apparatus contains filters to remove dirt or foreign matter entrained in the air and a dehumidifier to remove excess moisture and/or to cool the supply air. Air from both the primary and secondary apparatus is delivered to separate terminal units disposed in each of the enclosed areas through duct work forming a part of a primary air supply circuit and a part of a secondary air supply circuit.

A refrigeration machine is necessary to complete the overall system. Any of the three basic refrigeration cycles, absorption, reciprocating or centrifugal, may be considered for the refrigeration equipment. Either chilled water from the refrigeration machine or direct expansion of refrigerant may be used to obtain the desired temperature for the supply air. Preferably, to obtain the benefits of the invention disclosed herein, direct expansion should be employed whereby a refrigerant such as dichlorodifluoromethane, marketed under the trade name of "Freon-12," is controllably expanded into the dehumidifier coils to obtain the desired supply air temperature.

The air conditioning system disclosed herein is particularly useful to provide conditioned air to multizone buildings, such as schools, offices, apartments and hospitals, where individual room temperature control is desired. The system is particularly adaptable for modular buildings, zoned by solar exposure. Heretofore, where buildings have been zoned by solar exposure, primary air system has been designed to handle transmission load, that is either a heating or cooling load resulting from the difference between the temperature in the building and the ambient temperature, and solar load, that is cooling load caused by the rays of the sun warming the air in the buildings, and the secondary air has been designed to offset the cooling load in each of the enclosed areas supplied by people, lights and machinery, etc.

When the primary air system is sized for solar as well as transmission load compensation, it is necessary to adjust the primary air temperature for both solar and outside or ambient temperature variations. Compensation for ambient temperature variations is relatively simple, and devices to accomplish this are readily available. However, solar compensating devices are relatively expensive, complicated, and require excessive maintenance to keep same operating as desired.

The object of this invention is an air conditioning system of the dual conduit type, whereby the temperature of the primary air is readily adjusted to compensate for ambient temperature and/or solar load variations without the problems heretofore encountered.

SUMMARY OF THE INVENTION

This invention relates to a dual conduit system having a first airstream supplied to each of the areas being served by the system, said airstreams being at a constant volume and variable temperature and will be hereinafter referred to as primary air.

The airstream will include a second airstream which is at a constant temperature and which may be regulated by the individual occupant of all the areas except one to vary the volume to obtain desired temperature control. This airstream will be hereinafter referred to as secondary air.

A supply of secondary air is delivered to one of the areas being served by the system, this area having been preselected as one having a relatively constant people, light and machinery cooling load. This area will be hereinafter referred to as the "control" area. The temperature of the area is sensed and a signal related thereto is generated. The signal operates to control the operation of the apparatus regulating the temperature of the primary air. Primary air at the temperature related to the signal is supplied to each of the enclosed areas. Simultaneously with the supply of the secondary air to the control area, secondary air is supplied to each of the other areas in the building. The occupant of the other enclosed areas may adjust appropriate controls associated with the terminal in the area connected to the secondary air supply circuit to vary the volume of secondary air being supplied thereto to obtain desired temperature conditions in each of the areas.

BRIEF DESCRIPTION OF THE DRAWINGS

The FIGURE of the drawing is a schematic diagram showing the dual conduit type air conditioning system of the present invention.

DESCRIPTION OF THE PREFERRED EMBODIMENT

Referring now to the drawing, an air conditioning system 10 incorporating the present invention is shown. Air-conditioning system 10, which may be described as a central station type, includes an air conditioning equipment section designated generally by the numeral 12, and a conduit system 14, 15, for conducting primary and secondary air, respectively, to each of the areas or room 18 of the building served by the air conditioning system. Equipment section 12 maybe in the basement or on the roof of the building.

For the purposes of this description, primary air may comprise fresh air or ventilating air drawn from the outdoors, or a mixture of outdoor and return air treated in section 12, while secondary air may comprise air returned from the areas being conditioned and treated in section 12. The apparatus for conditioning the primary air preferably includes a filter 24 to remove foreign matter entrained in the air, heating or reheat coil 26 to elevate the temperature of air flowing in the primary air system or circuit and a cooling or dehumidifying coil 25 to remove excess moisture and/or cool the supply air as required, arranged in series flow relationship and encased within a suitable housing 28. The passage of primary air over coils 25 and 26 is regulated by dampers 59 and 60.

The portion of the central station equipment regulating secondary air preferably includes a suitable filter 30 to remove foreign matter entrained in the air and a dehumidifier or cooling coil 31 to remove the excess moisture and/or cool the supply air, arranged in series flow relationship and encased within a suitable housing 32.

Housings 28 and 32 are connected by duct 33 with return air and exhaust fan 34. The inlet of fan 34 is connected with return air plenum 40, which is connected by suitable means (not shown) with the areas or enclosed rooms 18 being served by the air conditioning system 10. Preferably, inlet air control

vanes 35 are provided to vary the flow of air through fan 34. Adjustable vanes 36 are provided to vary the flow of return air to the primary air conditioning apparatus. Exhaust dampers 37 connect duct 33 with the outdoors. Dampers 37 control the volume of return air discharged to the atmosphere.

Housing 28 connects with primary air fan 38. Conduit means 14 conveys primary air from fan 38 to the areas or rooms 18 being conditioned. Runout conduits 42 lead to the individual rooms 18. Runout conduits 42 each have at least one outlet terminal 44 for discharge of supply air to the room.

Housing 32 is connected with the outlet of return air fan 34. Preferably, adjustable vanes 45 are provided to vary the flow of supply air to the secondary air conditioning apparatus. Adjustable vanes 46 are provided to regulate the flow of outdoor air to the secondary air conditioning apparatus.

Conduit means 15 conveys air from fan 47 to the area or rooms being conditioned. Runout conduits 48 have one or more individual rooms 18. Runout conduits 48 have one or more outlet terminals 49.

The temperature of the primary and secondary air being conditioned by the primary and secondary conditioning apparatus is regulated by the operation of refrigeration machinery 50. Refrigeration machinery 50 represents any one of the three basic refrigeration cycles. The refrigeration machinery supplies a relatively cold medium to the dehumidifying coils 25 and 31 to regulate the temperature of the primary and secondary air. In the preferred embodiment, the relatively cold medium is dichlorodifluoromethane, marketed under the trade name of "Freon-12," or a similar refrigerant which may be directly expanded through valves 51 and 52 into the respective dehumidifying coils. The cold medium is supplied from the refrigeration machinery by conduit 53 and is returned thereto by conduit 54 and pump 55.

Each of the enclosed areas has a thermostat 56, which senses the temperature of the particular room. One of the thermostats 56' generates a signal related to the sensed temperature. The thermostat 56' is of a conventional type well known to those skilled in the art. The signal generated thereby is supplied to damper controllers 61 and 62. In the preferred embodiment, the control signal from thermostat 56' is pneumatic. However, it is within the scope of the invention for such signal to be electric. The signal operated to position dampers 59 and 60 to regulate the flow of air over coils 25 and 26 or about same to bypass the coils so the primary air temperature may be varied in a range from 55° F. to 125° F. The manner in which same is accomplished shall be more fully explained hereinafter.

OPERATION

As noted hereinbefore, a dual conduit system is designed to permit temperature regulation by the occupants of each of the enclosed areas 18 to obtain desired temperature conditions in each of said areas. The secondary air supplied to each of the areas basically compensates for cooling loads supplied by people, lights, machinery, etc. The primary air supplied to each of the enclosed areas is designed to compensate for transmission losses or gains caused by variations in the temperature of the outside or ambient air. In addition, the primary air is designed to compensate for changes in the cooling load caused by variations in the solar effect on each of the areas.

As noted above, difficulties have been encountered when solar compensating devices have been utilized with systems of the type described above. To obviate such difficulties, the present invention discharges a constant volume of secondary air through terminal 49' located in what is hereinafter referred to as a control room or area, that is, a room which has been preselected as having a relatively constant people, light and machinery cooling load. A reception area is typical of such a control area. The constant volume of secondary air substantially compensates for the above-mentioned cooling load in the area. The room thermostat senses the temperature of the room; any increase or decrease of temperature above the

design operating point is indicative of the transmission or solar load factors operating thereon.

A control signal related to the sensed temperature is generated and is supplied to the damper controllers 61 and 62. 5 Controllers 61 and 62 position dampers 59 and 60 to regulate the flow of primary air over coils 25 and 26. When cool air is required, the control signal operates to position damper 59 so the flow of primary air is routed over coil 25 and additionally operates to position damper 60 so the flow of primary air bypasses coil 26. As less cooling is required, damper 59 is positioned to bypass a portion of the primary air about coil 25.

When the thermostat senses heating is required, due to a negative transmission load, that is, heat is flowing from the enclosure to the ambient air, the control signal supplied to 15 damper controller 62 is operable to position damper 60 to direct the primary air over heating coil 26 and is additionally operable to position damper 59 via controller 61 to completely bypass dehumidifying coil 25.

20 Primary air, at a temperature controlled by the quantity of air being routed over or bypassed about the primary air coils 25 and 26, is passed from the primary air supply fan 38 through conduit means 14 to each of the areas or rooms being conditioned. As noted hereinabove, the primary air supplied to each of the rooms is at a constant volume. The primary air is thus applied at a temperature operable to compensate for transmission and/or solar factors.

Simultaneously with the supply of the constant volume of secondary air to the control area, secondary air is also supplied to each of the other areas. The room terminals in such areas are regulated to provide a varying volume of the secondary air to each of the areas. Volume regulation may be obtained by having the room thermostat sense the temperature and provide a control signal to position the damper means 35 regulating the supply of secondary air. The damper control signal may be pneumatic or electric. Thus, by regulation of the supply of secondary air to each area, a predetermined temperature condition may be obtained for each area irrespective of the temperature in any other area.

40 It is readily apparent that the air conditioning system disclosed herein operates to provide temperature regulation for each of the areas in an enclosure without having the problems heretofore encountered when solar compensation has been provided. The system readily compensates for solar load deviations by operating in the manner described above.

While I have described and illustrated a preferred embodiment of my invention, it should not be limited thereto but may be otherwise embodied within the scope of the following claims.

50 I claim:

1. A method of air conditioning a building containing a plurality of enclosed areas, having first and second central station conditioning apparatus for supplying respectively, conditioned primary and secondary air to each of the enclosed areas comprising the steps of:

- 60 A. supplying a constant volume of secondary air to a preselected enclosed area;
- B. sensing the temperature of the air in the preselected enclosed area;
- C. generating a signal, the magnitude thereof being related to the temperature of the air in the enclosed area;
- D. supplying a constant volume of primary air to each of the enclosed areas, the temperature thereof being related to said signal; and
- E. supplying secondary air to each of the other enclosed areas simultaneously with the supply of secondary air to said preselected enclosed area, the volume thereof being controlled to obtain the desired temperature for said area.

2. An air conditioning system for conditioning the air in a plurality of enclosed areas in a building including first and second central station conditioning apparatus for supplying primary and secondary air to each of the enclosed areas comprising:

- A. means for supplying a constant volume of secondary air to a preselected enclosed area;
- B. means for sensing the temperature of the air in said preselected enclosed area including means for generating a control signal related thereto;
- C. means operable to receive the control signal to regulate the operation of said first central station conditioning apparatus to supply a constant volume of primary air at a temperature related to said control signal to each of the enclosed areas; and
- D. means for supplying conditioned secondary air to each of the other areas in the enclosure simultaneously with the supply of secondary air to said preselected area, said means including means to vary the volume of secondary

15

air supplied to each of said other areas, said last-mentioned means operating to obtain the desired temperature for said area.

- 3. The method in accordance with claim 1 wherein the supply of primary air is operable to regulate the temperature of the air in each of the enclosures to compensate for transmission losses and solar load factors present in each of the areas.
- 4. The air conditioning system in accordance with claim 2 wherein the primary air supplied to each of the areas compensates for transmission losses and solar load factors present in the area.
